TAPERING COMB FOR THE HAIR

Leonora L. Marrello, 2328 E. Alma, Stockton, Calif.

Filed Apr. 18, 1962, Ser. No. 69,760

Term of patent 7 years

(Cl. D86—8)

FIG. 4

I claim:

The ornamental design of a tapering comb for the hair, as shown.
